UNITED STATES PATENT OFFICE.

FRED GÜNTHER, OF PERU, ILLINOIS.

SILO SEAL.

Application filed March 19, 1927. Serial No. 176,793.

The present invention is concerned with the provision of sealing means for preventing the fermentation and spoiling of ensilage, particularly with the provision of a silo seal of the general character disclosed in my prior Patent No. 1,611,025 dated December 14, 1926.

An object of the present invention is to improve the construction shown in the prior patent both by rendering the same more efficient and by standardizing the parts to render the device more suitable for purposes of economical manufacture.

The specific object of the invention is to improve the means for sealing the edges of the compressing cap which covers the ensilage.

Another specific object of the invention is to provide means for rendering the pressure on the sealing cap more uniform and readily adjustable.

Further objects are to provide a silo seal of simple, rugged construction which may be readily assembled within the silo and readily removed therefrom.

With the above noted and other objects in view, the invention consists in certain novel features of construction, and combinations and arrangements of parts, as will be more fully hereinafter set forth and pointed out in the claims. The invention may be more fully understood from the following description in connection with the accompanying drawings, wherein—

Fig. 1 is a fragmentary vertical sectional view through a silo illustrating my improved seal in applied position.

Fig. 2 is an enlarged longitudinal sectional view through one of the anchoring and coupling members for the tie bars and struts.

Fig. 3 is a sectional view of the slotted sealing ring which prevents the passage of air around the edges of the cap.

Fig. 4 is a diagrammatic sectional plan view of the edge sealing member showing the position assumed by the latter when in applied position.

Fig. 5 is an enlarged detail sectional view through the edge of the cap and the silo wall showing the seal in applied position.

Fig. 6 is a top plan view of the assembled sealing cap.

Fig. 7 is a bottom plan view thereof with the edge sealing ring omitted.

The device of the present invention includes a weighted sealing cap resting di-

rectly on the top of the ensilage, and serving to maintain the same in compressed and air-tight condition. This cap is preferably associated with a vertically disposed guiding means, and the guiding means preferably carries an anchor of considerable weight embedded in the ensilage and acting to hold the cap tightly in place.

In the drawings I have used the numeral 10 to designate a silo wall and 11 the ensilage stored therein. A relatively heavy anchoring member 12 buried in the ensilage is connected to a rod 13 rising centrally and vertically through the ensilage and guiding the sliding movement of a sealing cap composed of a plurality of segmental sections 13. In addition to providing for vertical movement of the cap, the rod 13 preferably carries a collar 14 bearing against the apices 75 of the segmental sections 13 which latter cooperatively define a central opening through which the rod passes. Thus the weight of the anchor is applied directly to the cap at the center and indirectly through mechanism which I shall later describe.

Preferably the under face of the circular cap defined by the cooperating and mating segmental sections 13 is lined with tar paper. This tar paper lining may comprise a series 85 of overlapping tar paper sheets 15 seen in Fig. 7 which prevent passage of air between the abutting edges of the cap sections 13. The space between the cap and the silo wall is sealed by a ring member 16 which may 90 be either continuous or formed with a plurality of overlapping sections. The ring 16 of tar paper or similar material is inwardly transversely slotted as at 17 from one edge so that when the paper is bent along a longitudinal line there will be provided a depending flange 18 disposed between the ensilage and the silo wall and an inwardly presented horizontal flange 19 under the edge of the cap formed by the tongues defined by 100 the slots 17. As the paper is longitudinally curved in accordance with the curvature of the silo walls, these tongues will overlap as indicated in Fig. 4, and form an effective seal.

The segmental sections 13 may be connected on their upper surfaces by a plurality of boards 20, the intermediate portions of which overlie the abutting edges of the segmental sections, and the ends of which abut 110 each other, these boards forming a concentric series of polygonal braces and conne-

tors, the number of sides of the polygons being predetermined by the number of segmental sections used to complete the circular cap. The adjacent ends of the boards 20 of the outer ring are connected by short lengths of pipe or tubing 21 serving as fulcrums or anchorages for castings 22 one of which is shown in Fig. 2. These castings include notches 23 in their under faces rockably receiving the pipes 21. Substantially horizontal bores 24 receive tie rods 25 and inwardly upwardly facing inclined members such as the sockets of Fig. 1 or the stud 26 of Fig. 2 receive the lower outer ends of 15 inclined struts 27.

The inner ends of the tie rods 25 are hooked as at 28 for engagement with a common central anchoring ring 29 surrounding the upper end of the rod 18, and nuts 30 20 screwed on to the threaded outer ends of the tie rods render it possible to tighten them and cause the ring 29 to exert a downward pressure on the center of the sealing cap due to the fact that the tie rods near their inner 25 ends rest on blocks 31 fixed to the cap.

The upper inner ends of the struts 27 bear against the dished under face of a collar 32 30 slideable on a rod 33 and spring pressed downwardly by a coiled torsional spring 34 35 encircling the rod between the collar and a washer 35 held in place by a nut 36 screwed on to the threaded end 37 of the rod. The lower end of the rod 33 and the upper end of the rod 13 are hooked so that they may be connected by a chain 38 or equivalent flexible device.

From the foregoing description it will be seen that the anchor 12 exerts a direct downward pressure on the center of the seal, and 40 acts through the medium of struts 27 to exert a downward pressure on the outer edges of the seal. This pressure is increased by the spring 34 and the central pressure may be increased by tightening the bars 25 and 45 causing them to bear down upon their supporting blocks 31. Obviously the anchor might be eliminated and a stationary guide member provided at the center of the silo, which guide member might be anchored in 50 the ground. As the spring pressure 34 gradually packs down the ensilage the spring will become less effective, but by the time it has lost its effectiveness and pushed the collar 32 down, the rod 33 will have become unnecessary, since the weight of the cap alone at 55 this time will be sufficient to maintain the ensilage in a compressed condition, the ensilage not being inherently expansive.

Obviously, various changes and alterations 60 might be made in the general form and arrangement of the parts described without departing from the invention. Hence I do not wish to limit myself to the details set forth, but shall consider myself at liberty 65 to make such changes and alterations as

fairly fall within the spirit and scope of the appended claims.

I claim:

1. A silo seal including a weighted airtight platform adapted to fit within a silo 70 and rest on the ensilage to seal and compress the same, an adjustable guide rod extending through the platform and guiding the vertical movement thereof, a block spring pressed downwardly and mounted adjacent the upper end of the rod, and inclined struts rockably connected to the platform near the edge of the latter and having their inner upper ends arranged under the block to transmit the downward spring pressure of the same 80 to the platform.

2. A silo seal including a weighted airtight platform adapted to fit within a silo and rest on the ensilage to seal and compress the same, an adjustable guide rod extending 85 through the platform and guiding the vertical movement thereof, a block spring pressed downwardly and mounted adjacent the upper end of the rod, and inclined struts rockably connected to the platform near the 90 edge of the latter and having their inner upper ends arranged under the block to transmit the downward spring pressure of the same to the platform, the platform comprising a plurality of segmental complementary sections and the means for rockably mounting the ends of the struts, including stationary members bridging the adjacent edges of two platform sections and upon which strut carrying members are 100 rockably mounted.

3. A silo seal including a weighted airtight platform adapted to fit within a silo and rest on the ensilage to seal and compress the same, an adjustable guide rod extending 105 through the platform and guiding the vertical movement thereof, a block spring pressed downwardly and mounted adjacent the upper end of the rod, and inclined struts rockably connected to the platform near the edge 110 of the latter and having their inner upper ends arranged under the block to transmit the downward spring pressure of the same to the platform, the adjustable guide rod comprising a pair of aligned guide rod sections and an adjustable flexible device connecting them, whereby the lower section is 115 hung from the upper section.

4. A silo seal as set forth in claim 3, and wherein an anchor is carried by the lower 120 section and embedded in the ensilage and a collar on the lower section transmits the weight of the anchor directly to the platform before the latter has been gradually depressed by the spring.

5. A silo seal including a weighted airtight platform adapted to fit within a silo and rest on the ensilage to seal and compress the same, a sealing ring lying between the 125 ensilage and silo wall and including a flange 130

projecting inwardly, overlying the ensilage and disposed under the outer edge of the platform.

6. A silo seal including a weighted airtight platform adapted to fit within a silo and rest on the ensilage to seal and compress the same, a sealing ring lying between the

ensilage and silo wall and including a flange projecting under the outer edge of the platform, said ring being of readily bendable material and the flange being slotted to provide overlapping tongues. ¹⁰

FRED GÜNTHER.
